Primary Examiner — John Windmuller*Assistant Examiner* — Steven J Czyz*(74) Attorney, Agent, or Firm* — Schrantz Law Firm, PLLC; Stephen D. Schrantz(57) **CLAIM**

The ornamental design for a needle installation and extraction device, as shown and described.

DESCRIPTION

FIG. 1 is a top perspective view of a needle installation and extraction device with environment, showing my new design;

FIG. 2 is a top perspective view of the needle installation and extraction device, shown without environment;

FIG. 3 is a bottom perspective view thereof;

FIG. 4 is a front view thereof, the rear view being a mirror image of the front view;

FIG. 5 is a left side view thereof;

FIG. 6 is a right side view thereof;

FIG. 7 is a top view thereof;

FIG. 8 is a bottom view thereof; and,

FIG. 9 is a perspective view of the needle installation and extraction device, shown in use with environment.

The broken lines depict environment that forms no part of the claimed design.
